UNITED STATES PATENT OFFICE.

GEORGE MITCHELL, OF LONDON, ENGLAND.

APPARATUS FOR MAKING EMULSIONS.

1,393,632.

Specification of Letters Patent. Patented Oct. 11, 1921.

Application filed November 1, 1920. Serial No. 420,956.

To all whom it may concern:

Be it known that I, GEORGE MITCHELL, a subject of the King of England, residing in London, England, have invented certain new and useful Improvements in Apparatus for Making Emulsions, of which the following is a specification.

This invention is for improvements in or relating to apparatus for making emulsions and has for its object to provide an improved construction of apparatus in which solid or semi-solid materials, which contain oil and are difficult to break up and emulsify in water or other liquid, can be thoroughly and successfully emulsified. As an example of such materials may be mentioned the kernels of castor seed which contain approximately 65% of oil and have hitherto been found difficult to break up and emulsify. The apparatus is also suitable for treatment of other materials which are more readily emulsified.

An apparatus according to the present invention comprises the combination with a chamber having at the bottom thereof a narrow outlet in the form of a slit of a width approximately equal to, say, the thickness of a paper sheet, and means for masticating in liquid in the chamber the material to be emulsified and for forcing the liquid containing the masticated material through said outlet.

In a preferred form the apparatus comprises two members spaced apart face-to-face, means to effect relative movement between them, and means for introducing the material between them and for discharging it at their margins, characterized by corrugations on the inner face of one member (or on the inner faces of both members) which corrugations are disposed obliquely to the direction of relative movement between the members and constitute pockets diminishing in depth toward the discharge edge aforesaid at which edge a narrow (preferably adjustable) gap is afforded between the members equal to, say, the thickness of a paper sheet.

Conveniently the two members are both circular in plan, one of them being stationary and the other movable, and the corrugations are formed between volute ribs standing on the movable member and of such a depth that each approximately fills the space between the two members, the leading face of each rib being curved from the

top of the rib by an easy curve uniting the top of the rib and the root of an adjacent rib.

Preferably the curve uniting the top of a rib with the root of an adjacent rib is gradually flatter as it approaches the outer extremity of a corrugation.

A feature of the invention comprises a construction in which each of the two members is of conical form and the fixed member is in the form of a hood for the movable member, the degree of conicity of the floor of the movable member on which the ribs are formed being less than that of the fixed member.

According to another feature of the invention there are corrugations on the fixed member disposed around the marginal discharge edge portion thereof, each corrugation extending in an oblique direction in relation to a radius of the member and the trough of each corrugation being preferably dished both in the direction of its length and also in a transverse direction.

Other features of the invention comprise an annular collecting trough and a cover for the casing to be more fully described hereinafter.

One preferred form of apparatus will now be described, by way of example, with the aid of the accompanying drawings, in which—

Figure 1 is a central sectional elevation through the apparatus;

Fig. 2 is a central sectional elevation at right-angles to Fig. 1;

Fig. 3 is a plan view of Fig. 1 with the cover plate removed;

Fig. 4 is a view of the underside of the cover plate;

Fig. 5 is a section through one of the corrugations of the cover-plate on the line 5—5 of Fig. 4 drawn to a larger scale;

Fig. 6 is a series of transverse sections on the lines a—a to g—g of Fig. 5;

Figs. 7—9 are fragmentary sectional views on the lines 7—7 to 9—9 respectively of Fig. 3, to a larger scale.

Like reference letters indicate like parts in all the figures.

The apparatus is inclosed in a cylindrical casing A of cast-iron or other desired material closed at the bottom and open at the top. A cover B for the top of the casing is formed of material of a similar nature to that of the casing and this cover forms one of the two

2

coöperating crushing members to be more particularly described hereinafter. It is conveniently secured to the casing by bolts pivotally mounted in a flange around the upper edge of the casing and arranged to swing into slots formed in the peripheral portion of the cover, in which position they are secured by means of nuts.

On the inner periphery of the casing is formed, by casting or otherwise, an annular channel A^1 which is shallower at one side of the casing than at the other and its bottom slopes gradually downward from one end of a diameter of the casing to the other end thereof. At its lowest point the channel discharges through an outlet A^2 opening through the side of the casing.

The cover B , which constitutes the fixed member of the pair of crushing members, is conical in form and has, at its central part, a flanged tubular inlet B^1 . The inner face of the cover is formed near its margin, and over the mouth of the annular channel A^1 , with a sharply defined edge B^2 and the extreme outer margin beyond this edge is inclined upwardly toward the flange by which it is secured to the casing. This sharply-defined edge is at a position at which the emulsified material will be discharged.

Directed inwardly from this edge and completely around the surface of the inner face of the cover, is a plurality of corrugations B^3 evenly spaced and inclined more or less tangentially, as clearly indicated in Fig. 4. That is to say they are each arranged obliquely to a radius of the cover. The separating ribs B^4 of the corrugations have their edges formed on the general line of the cone on which the inner surface of the cover is shaped. The troughs of the corrugations extend inwardly from the discharge edge for a small distance only, say for about one-fifth of the length of the working surface of the cover measured from the discharge edge toward the center. The troughs are arc-shaped in section in both directions and in the transverse direction they are substantially flattened at both extremities but have a considerably greater curvature at a central section intermediate the two extremities, as will be clearly seen from an examination of Figs. 5 and 6. Thus, the corrugations B^3 constitute a plurality of separated pockets around the periphery of the inner face of the cover.

The movable member C is in the form of a disk having a conical surface whereof the degree of conicity is less than that of the inner face of the cover. At its central portion the disk tapers in a smooth curve upwardly toward a point C^1 in the central axis of the cone and this pointed portion extends centrally within the tubular inlet B^1 in the cover B . Thus, between the cover B and

the movable member C there is afforded an annular inlet for the material to be emulsified leading into a chamber C^2 formed between the two members. This chamber C^2 will be hereinafter referred to as the masticating chamber.

On the upper face of the movable member C there are formed a number of volute ribs C^3 the inner ends of which commence substantially tangentially near the base of the sharply tapered central portion. At their trailing edges these ribs are formed with vertical faces but the leading face of each rib is curved from its top edge in an easy curve toward the root of the vertical edge of an adjacent rib, as shown in Figs. 7-9. As the masticating chamber C^2 , constituted by the space between the cover and the movable member tapers gradually from the center toward the discharge edge, the volute ribs C^3 will also taper in depth in a similar manner as they are of such a depth that they each approximately fill the space between the cover and the movable member. Referring again to Figs. 7-9, it will be observed that the degree of curvature of the channels between the ribs is also considerably less near the outer periphery than toward the center. At the periphery immediately beneath the discharge edge B^2 of the cover these channels are of such a depth that between the cover and the surface or floor of the channels there is only a narrow slit provided. In the region of this discharge edge the surface of the movable member is flanged downwardly and this flange overhangs the upper edge of the annular channel A^1 referred to above.

The movable member C is mounted for rotation on the upper end of a vertical shaft D journaled centrally in the casing in two bearings. Of these two bearings the lower one D^1 is a footstep bearing formed in an enlargement provided in the base of the casing. The other bearing for the shaft is situated near its upper end and is carried centrally in a spider D^2 , the outer ends of the arms of which are secured to, or cast integral with, the inner wall of the annular collecting channel A^1 . The actual bearing at this end of the shaft is constituted by a bushing D^3 which is vertically adjustable by means of a screw-threaded engagement with a central boss D^4 on the spider and the bush is provided with a hand-wheel D^5 at its lower end by which it may be rotated to effect its vertical adjustment. A lock-nut D^6 , also formed with a hand-wheel, is provided to retain the bushing in its adjusted position.

The shaft D , at its upper end, extends into a central recess E in the lower face of the movable member C and is slidably keyed therein. Between the lower face of the movable member and a flange F formed

at the upper end of the bushing D^2 just referred to, is a ball-bearing G on which the member C is supported and rotates. It is thus possible, by rotating the hand-wheel

5 D^5 , to adjust the height of the member C , and it will be seen that any such adjustment will have the effect of altering the width of the discharge gap between the outer edge of the disk and the edge B^2 on the cover-plate.

10 In order to rotate the shaft there is keyed to it, at its lower end, a bevel-pinion H which meshes with a second bevel-pinion J carried at the inner end of a horizontal shaft K . The latter is carried in bearings 15 K^1 provided on the inner wall of the casing A and at its outer end beyond the casing, is provided with a sprocket K^2 or other convenient driving connection by which it can be rotated.

20 The operation of the apparatus is as follows:

The material to be emulsified, for example the kernels of castor seed in admixture with water, is fed through the inlet B^1 25 in the cover on to the movable member C which latter is rotated by the mechanism just described. Partly by the aid of centrifugal action and partly owing to the shape of the ribs C^3 , the material is fed 30 toward the circumference of the movable member and becomes emulsified during its passage. Owing to the diminishing depth of the ribs, the solid material becomes crushed and this crushing action is aided 35 by the corrugations B^3 at the periphery of the cover or fixed member. At the discharge edge the two members are separated only very slightly for example a distance equal to the thickness of a paper sheet 40 and the material becomes further emulsified by being forced through this very narrow slit. The emulsified material issues from the discharge edge as a creamy substance which is thrown out into the annular 45 collecting channel A^1 and from this channel it flows by gravity to the discharge outlet A^2 .

It is found that with the present apparatus materials which are very difficult to 50 emulsify, for example the kernels of castor seed, are very thoroughly and efficiently broken up and emulsified.

What I claim as my invention and desire to secure by Letters Patent is:

5 1. An apparatus for making emulsions, comprising two members spaced apart face to face, means for producing relative movement between said members, and means for introducing material between said members 0 and for discharging the material at their margins, at least one of said members having corrugations on the inner face thereof disposed obliquely to the direction of relative movement between the members of the

troughs of said corrugations diminishing in 65 depth toward the discharge margin at which a narrow gap is afforded, substantially as described.

2. An apparatus for making emulsions, comprising two conically shaped members 70 spaced apart face to face to provide a downwardly inclined masticating chamber therebetween, means for producing relative movement between said members, and means for introducing material into said 75 chamber, said members forming a narrow discharge gap adjacent the edges thereof through which the material is discharged, at least one of said members having corrugations on the inner face thereof disposed obliquely to the direction of relative movement between the members, the troughs of 80 said corrugations diminishing in depth toward said discharge gap, substantially as described.

3. An apparatus for making emulsions, comprising in combination, two members spaced apart face to face to provide a masticating chamber therebetween, means for producing relative movement between said 90 members, means for introducing material between said members and for discharging it at their margins, and an annular collecting trough to receive the discharged material and formed with its bottom surface 95 sloping downwardly from one end of a diameter of said members to an opposite end thereof, at least one of said members having corrugations on the inner face thereof disposed obliquely to the direction of relative 100 movement between the members, the troughs of said corrugations diminishing in depth toward their discharge margins, substantially as described.

4. An apparatus for making emulsions, 105 comprising a member having a conically shaped face provided with volute ribs upstanding therefrom, a second member co-operating therewith and provided with corrugations constituting pockets diminishing 110 in depth toward the outer edge of said members, means for producing relative movement between said members, and means for positioning said members to provide a narrow discharge gap between the edges there- 115 of, substantially as described.

5. An apparatus for making emulsions, comprising a bottom member having a conically shaped upper face provided with volute ribs, an upper member co-operating therewith, and provided with corrugations constituting pockets adjacent the edge of said member, means for producing relative movement between said members, and means for holding said members in co-operative relation to provide a narrow discharge gap between the edges thereof, substantially as described.

6. An apparatus for making emulsions comprising a movable member having a conically shaped face provided with volute ribs upstanding therefrom, a conically shaped fixed member in the form of a hood for the movable member and coöperating therewith to form a downwardly inclined masticating chamber, the degree of conicity of the surface of the movable member on which the ribs are formed being less than that of the adjacent surface of the fixed member, and means for rotating the movable member, substantially as described.
7. An apparatus for making emulsions, comprising a circular bottom member, having a series of upstanding volute ribs thereon gradually decreasing in height from the center of said member outwardly, a second member coöperating therewith, and means for producing relative rotational movement between said members, substantially as described.
8. An apparatus for making emulsions comprising an upper member, a circular bottom member coöperating therewith to form a masticating chamber and having a series of volute ribs each shaped to fill approximately the space between the two members, with the leading face of each rib carried from the top thereof by an easy curve uniting the top of the ribs with the foot of an adjacent rib, and means for producing relative rotational movement between said members, substantially as described.
9. An apparatus for making emulsions comprising a circular bottom member having a series of volute ribs thereon each provided with a vertically extending face and a curved face, said ribs gradually decreasing in height from the center of said member outwardly whereby said curved faces gradually become flatter toward the periphery of said member, a second member coöperating therewith to form a masticating chamber, and means for producing relative rotational movement between said members, substantially as described.
10. An apparatus for making emulsions, comprising a casing having a conically shaped cover provided with corrugations, the troughs of which gradually diminish in depth toward the outer edge of said cover, an annular collecting trough below said cover, a rotatable member within said casing and coöperating with said cover to provide a masticating chamber therebetween,
- and means for rotating said member, substantially as described.
11. An apparatus for making emulsions, comprising a casing having a conically shaped cover provided with corrugations the troughs of which gradually diminish in depth toward the outer edge of said cover, an annular collecting trough in said casing below said cover, a rotatable member within said casing and coöperating with said cover to provide a masticating chamber therebetween, said rotatable member having a series of volute ribs upstanding therefrom in the direction of the cover aforesaid, and means for rotating said member, substantially as described.
12. An apparatus for making emulsions, comprising a stationary member having corrugations formed in the marginal portion of one face thereof, the troughs of said corrugations gradually decreasing in depth from the middle toward the ends and toward both sides thereof, a second member coöperating therewith to provide a masticating chamber therebetween, said chamber having a marginal discharge gap, means for feeding material to said chamber, and means for producing relative rotational movement between said members, substantially as described.
13. An apparatus for making emulsions, comprising coöperating conically shaped members forming a masticating chamber therebetween, a series of volute ribs of gradually decreasing height formed on one of said members, and extending substantially entirely across said chamber, and means for producing relative rotational movement between said members, substantially as described.
14. An apparatus for making emulsions, comprising a casing having a conically shaped cover provided with corrugations the troughs of which gradually diminish in depth toward the outer edge of said cover, an annular collecting trough in said casing below and closed by the said cover, a rotatable member within said casing and coöperating with said cover to provide a masticating chamber therebetween, said rotatable member having a series of volute ribs upstanding therefrom in the direction of the cover aforesaid, and means for rotating said member, substantially as described.

In testimony whereof I affix my signature.

GEORGE MITCHELL.
